UNITED STATES PATENT OFFICE.

GUY CLIFFORD OSBORNE, OF RANDALL, KANSAS.

ANTI-RAIL-SPREADING DEVICE.

1,197,536.

Specification of Letters Patent.

Patented Sept. 5, 1916.

Application filed September 21, 1915. Serial No. 51,803.

To all whom it may concern:

Be it known that I, GUY CLIFFORD OSBORNE, a citizen of the United States, residing at Randall, in the county of Jewell and 5 State of Kansas, have invented certain new and useful Improvements in Anti-Rail-Spreading Devices, of which the following is a specification.

My invention relates to railway safety appliances and more particularly to an improved anti-rail-spreading device.

The object of the invention is to generally improve in the construction of anti-rail-spreading devices in that the component 15 parts thereof may be so relatively arranged and interlocked as to positively preclude displacement of the mentioned parts and consequently relative movement of the railway rails.

20 The invention may be said to consist in the novel construction, combination and arrangement of parts hereinafter described and more particularly pointed out in the appended claim.

25 In describing my invention in detail reference will be had to the accompanying drawings wherein like characters denote like or corresponding parts throughout the several views, and in which:

30 Figure 1 is a side elevation of my improved anti-rail-spreading device, partly broken away, the railway rails in connection with which the device is being used being shown in transverse section; Fig. 2 is a top plan view of the device as illustrated in 35 Fig. 1; Fig. 3 is a detail perspective view of one of the underlying wedge shaped rail engaging parts; and Fig. 4 is a section on the line 4—4 of Fig. 1.

40 Referring now to the drawings by numerals, 1—1 designates the railway rails and 2 the cross ties to which the mentioned rails are fastened in a manner common to the art. The device of my invention, designated as an entirety by the numeral 3 is of a construction and size to enter the space between the mentioned ties and to engage both the inner and outer faces of the respective railway rails.

45 In its preferred embodiment the anti-rail-spreading device 3 may be said to consist of a spreading bar designated as an entirety by the numeral 4 and complementary interlocking underlying wedge shaped members designated respectively 5 and 6. The 55 terminals of the spreading bar 4 are some-

what enlarged as indicated at 7 to overlap and positively contact with the inside base flange of the rails 1 and through such positive engagement maintain the mentioned 60 rails properly spaced and at all times in substantially parallelism. An integral band or collar 8 is formed upon the spacing bar 4 adjacent each end thereof to engage and embrace the respective underlying rail engaging members 5 and 6, such engagement acting as a brace for the mentioned members and maintaining the component parts of the complete device in contiguous or engaging relation when properly assembled as shown 70 to advantage in Fig. 1.

As suggested, the underlying rail engaging members 5 and 6 are of a wedge-shaped formation, each of the said members tapering to a point equi-distant from the terminals of the dividing or spacing bar 4. An enlargement 9 is formed upon the outer extremity of each of the mentioned members 5 and 6 to overlap and contact with the outside base flange of the rails 1 that the mentioned rails may be locked against displacement and in firm engagement with the terminals of the spacing bar 4.

Serrated extensions, designated respectively 10 and 11 are formed upon the inner terminals of the respective members 5 and 6, the mentioned extensions being adapted for overlapping and interlocking engagement in the manner shown. Each extension is provided with an opening 12 through which a fastening bolt 13 passes, the mentioned bolt 13 likewise fitting an opening 14 in the spacing bar 4 to be held in place by a removable nut 15 threaded on said bolt to engage with the top face of the spacing bar 90 4 that access may be gained thereto with facility and ease.

From the foregoing, taken in connection with the accompanying drawings it is evident that the rails 1 are positively locked 100 against relative movement; that the parts constituting the anti-rail-spreading device are so interlocked and arranged as to preclude casual displacement; and that but a single fastening bolt may be utilized to 105 maintain the said parts in the desired and assembled relation.

If desired, the contacting surfaces of the extensions 10 and 11 may be made perfectly smooth that the members 5 and 6 may be 110 readily slid into proper place.

In reduction to practice, I have found that

the form of my invention, illustrated in the drawings and referred to in the above description, as the preferred embodiment, is the most efficient and practical; yet realizing 5 that the conditions concurrent with the adoption of my device will necessarily vary, I desire to emphasize the fact that various minor changes in details of construction, proportion and arrangement of parts may 10 be resorted to, when required, without sacrificing any of the advantages of my invention, as defined in the appended claim.

Having thus fully described my invention, what I claim as new and desire to secure by 15 Letters Patent, is:—

An anti-rail-spreading device including a spreading bar of a length to engage with the

inner sides of the rails, fastening members 20 engaging the remote sides of the rails, and extending beneath the rails and toward each other centrally of the rails, bands formed integrally with the bar adjacent its terminals and embracing the members, corrugated terminals on said members for overlapping engagement, and a single bolt ex- 25 tending through the spreading bar and the overlapping terminals.

In testimony whereof I affix my signature in presence of two witnesses.

GUY CLIFFORD OSBORNE.
